Barnett & Truman,
Attorneys.

UNITED STATES PATENT OFFICE.

GEORGE W. BENDER, OF CHICAGO, ILLINOIS, ASSIGNOR TO MUDGE & COMPANY, OF CHICAGO, ILLINOIS, A CORPORATION OF ILLINOIS.

VENTILATOR.

Original application filed September 4, 1920, Serial No. 408,219. Divided and this application filed May 18, 1923. Serial No. 639,725.

To all whom it may concern:

Be it known that I, GEORGE W. BENDER, a citizen of the United States, residing at Chicago, in the county of Cook and State 5 of Illinois, have invented certain new and useful Improvements in Ventilators, of which the following is a specification.

My invention relates to ventilators for railway cars or the like, of the type in which 10 ventilation is induced by suction created by the impact of the air on a surface arranged at right angles to the direction of movement of the car.

It is one of the objects of my invention to 15 provide a new and improved form and arrangement of parts by which an improved operation may result.

Specifically it is one of the objects of my invention to arrange a mechanically operated suction device adapted to cooperate effectively with the ventilator when the car 20 is at rest.

Other objects of my invention will appear hereinafter.

25 The preferred means by which I have accomplished my several objects are illustrated in the accompanying drawing and are hereinafter specifically described.

That which I believe to be new and desire 30 to cover by this application is set forth in the claims.

In the drawing

Fig. 1 is a transverse sectional view 35 through a portion of a car equipped with my improved mechanism.

Fig. 2 is a horizontal sectional view taken on line 2—2 of Fig. 1.

Fig. 3 is a fragmentary, horizontal sectional view, taken on line 3—3 of Fig. 1.

40 Referring to the drawing, 10 indicates the upper deck, and 11 the lower deck of the clerestory of a car equipped with my improved ventilating mechanism of the general type illustrated in my copending application Serial No. 408,219, filed September 4, 1920, of which this application is a division, such prior application having resulted in Patent No. 1,469,577, dated October 2, 1923.

50 This mechanism comprises a centrifugal fan of any approved type through the body of which air is free to sweep when the fan is at rest. In the construction shown the fan comprises a casing 12 supported by a

standard 13 from a hanger 14 depending 55 from the upper deck 10. The rotary member of the fan comprises a plate 15 fixedly mounted on a shaft 16 so as to be rotated thereby. A plurality of plates 17 are arranged in spaced relation between the plate 60 15 and the ring 18, the arrangement being such that upon the rotation of the shaft in a clockwise direction in Fig. 1, air is drawn in through the opening 19 in the face of the casing and forced from the casing through 65 the pipe 20 as will be readily understood.

It will be appreciated that when the fan is at rest, there is nothing to prevent the free movement of air through the casing 12.

Upon the outer end of the pipe 20 I have 70 secured a transversely extending pipe 21 having a flange 22 at its outer end to which the ventilator is secured in any suitable manner. As will appear from Figs. 1 and 2, the ventilator comprises side plates 23 and 24, connected together in spaced relation by plates 25 and 26 which act as the air ramming faces. Between the plates 25 and 26, the plates 23 and 24 are connected by means of 75 two transverse plates 27 and 28, which are 80 diagonally disposed so as to converge toward their lower edges, being spaced apart and spaced from the air ramming faces 25 and 26. The plates 23 and 24 are also connected by means of two transverse plates 29 85 in position above the plates 27 and 28, only one of the plates 29 being shown. The plates 29 are also diagonally disposed, being arranged so as to converge toward their upper edges. Each of the plates 27, 28 and 29 90 is provided on its outer edge with an outwardly directed flange 29^a, as is best shown in Fig. 3. Longitudinally extending plates 30 and 31 are mounted in spaced relation on the transverse plates 27 and 28, and 95 longitudinally extending plates 32 and 33 similarly spaced are mounted on the transverse plates 29. The side plate 23 is provided with diagonally disposed flanges 34, 35, 36 and 37 about a central opening therein, the flanges being preferably formed integrally with the plate 23. The side plate 24 is provided with outwardly extending flanges 38 and 39, between which are secured 100 a plurality of plates 40 slanting outwardly and downwardly in the form of louvre.

In operation, when the car is stationary, the shaft 16 is to be driven from any suit-

able source of power, serving to drive the fan for carrying the air from the car through the ventilating device, the air so driven out finding ready escape between the 5 plates 40. When the car is in motion, however, the shaft 16 is to be at rest, whereupon the impact of the air upon the air ramming face 25 or 26 and the sweep of the air over the edges of such plates induce a stream of 10 air to flow outwardly through the ventilator in the now well understood manner. The sweep of the air past the outer edge of one of the plates 38 and 39 which is in advance 15 in the movement of the car, assists in the production of the induced current outwardly through the ventilator.

While I prefer to embody my invention in the form illustrated in the drawing, it will be understood that I do not wish to be restricted to the particular form shown, except so far as the same is specifically claimed, it being evident that various changes can be made in the form of structure without departing from the spirit of the invention. 20

25 I claim:

1. A hollow substantially rectangular box-like ventilator for railway cars having an air inlet passage in one face, the opposite face being substantially open, a plurality 30 of spaced slanting plates extending across said open face, air ramming faces disposed transversely to the direction of movement of the car, there being exhaust passages in the remaining two faces of the 35 ventilator, and spaced oppositely inclined plates in each of the exhaust passages disposed transversely to the air current deflected over said passages, the outer edges of said plates being arranged substantially in the planes 40 passing through the opposite edges of the air ramming faces.

2. A hollow substantially rectangular box-like ventilator for railway cars having an air inlet in one side face, the opposite side face being substantially open, a plurality 45 of downwardly slanted plates extending across said open side face, air ramming side faces disposed transversely to the direction of movement of the car, the top and bottom faces of the ventilator being substantially 50 open to form exhaust passages adjacent the said air ramming faces, and spaced oppositely inclined plates in each of the exhaust passages disposed transversely to the air current deflected over said passages, thus providing 55 exhaust passages at each side of each plate, the outer edges of such plates being arranged substantially in the planes passing through the opposite edges of the air ramming faces. 60

3. A hollow box-like ventilator for railway cars having an opening in its outer side face and having a plurality of downwardly slanted plates extending horizontally across said opening, said ventilator comprising air ramming faces disposed transversely to the direction of movement of the car, with exhaust passages adjacent to said air ramming faces, spaced oppositely inclined plates in each of the exhaust passages disposed transversely to the air current deflected over said passages, the outer edges of said plates being arranged substantially in the planes passing through the opposite edges of the air ramming faces, and 70 an exhaust fan connected with said structure and adapted to force a stream of air outwardly through the open side face and adapted to permit the free passage of air therethrough when not in operation. 75

GEORGE W. BENDER.
